ELECTRICAL CONTROL FOR CENTRIFUGAL
SEPARATING MACHINESJoseph S. Pecker, Philadelphia, Pa., assignor to
American Centrifugal Corporation, New York,
N. Y., a corporation of Delaware

Application December 26, 1934, Serial No. 759,302

36 Claims. (Cl. 210—72)

This invention relates to the control of electrically driven centrifugal machines and is particularly concerned with the control and cyclic operation of such machines used to extract the solid matter from sewage and other sludge.

The invention relates to means for slowly starting a centrifugal basket and setting into operation means for cleaning the basket, increasing the speed for normal operation, admitting sewage sludge and operating for a definite time cutting off supply of sewage sludge, slowing down the basket, and again cleaning. This cycle of operations is continued indefinitely, and automatically operating means is provided for that purpose.

An object of the invention is to provide a slow speed motor for starting and low speed operation, and a high speed motor for normal operation of the centrifugal machine, and to electrically interlock the circuits of these machines so as to bring about the desired sequence of operation of the motors.

A further object is to provide one or a plurality of cleaning blades in the basket for scraping the deposited material from the inner wall and moving it toward the center of the bottom of the basket where it passes out, these blades being intermittently operated in their movement from and toward the wall of the basket. A further object of the invention is to provide an electrical control adapted not only to provide a means for intermittently or periodically operating the scrapers or cleaning blades but which will also permit a continuous movement outwardly and inwardly of the cutters or scrapers. Another object is to interlock the circuits of the slow speed driving motor with the cleaner operating motor so as to bring about proper cooperation of these devices in cleaning the basket.

It is also an object to interlock the circuits of the inlet valve motor with those of the high speed motor and to provide time controlled means for controlling the operation of these motors. Other objects will be apparent from the detailed description of the apparatus.

Referring to the drawings, which are made a part of this application and in which similar reference characters indicate similar parts:

Fig. 1 is a side elevation of a centrifugal machine showing the general arrangement of the several motors controlling its operation,

Fig. 2 is a plan view taken on the section line 1—1 of Fig. 1,

Fig. 3 is a diagram of the circuit control for the cleaner motor, and

Fig. 4 is a diagram of the control and operating circuits of the machine.

Referring to Figure 1, the centrifugal machine is indicated generally at 1, the low speed driving motor at 2, the high speed motor at 3, the cleaner driving motor at 4, the inlet valve at 5 and the valve operating motor at 6. While the inlet valve 5 and the valve operating motor are shown in the accompanying drawings located at the top of the centrifugal separating machine, it will be readily understood that they may be located at any other desired point but controlled, nevertheless, from the control panel. The basket of the machine is located above and is driven through gearing located in the gear casing 7. The slow speed motor 2 is connected to the driving gears in casing 7 through a free wheeling or overrunning clutch 8 so that the slow speed motor will not be driven while the high speed motor is in operation, but will drive through the clutch 8 when the speed of the extractor has dropped to such an extent that the clutch can operate. While the motors 2 and 3 are referred to as low and high speed motors it will be appreciated that the speeds of these motors may so vary as to more nearly approach the same speed, particularly when changing over from cleaning to purging operation.

The cleaning mechanism within the basket of the machine is operated by the screw 9 which is reciprocated by the reversible cleaner motor 4 through the bevel gears 10 and 11. This motor 4 is controlled by reversing and limit switches shown in Figure 3 in interlocking relation with the other circuits of the system of control. A centrifugal governor 12 is driven by the high speed motor and controls the interlocked switches in the operating circuits of the high and low speed motors. While a centrifugal ball type governor has been shown as a speed responsive means for controlling the motors it will be understood that type of device is illustrative and that other speed responsive means, known in the art, electric or fluid operated, for instance may be employed to perform this function.

In Figure 2 is shown in plan and in enlarged scale the construction below the section on line 1—1 of Figure 1. In this figure the plate 13' has mounted thereon the screw 9 for operating the cleaning blades or scrapers 14, 15 which are located in the basket, shown in section at 16, and below the plane of plate 13'. These cleaning blades 14 and 15 are oscillated by means of rods 17 and 18 which are mounted in plate 13' and are themselves oscillated by arms 20 which have

projections 21 and 22 extending into openings in an extension 23 of the screw 9. This extension member 23 has a sliding bearing at 24 mounted on plate 13'. It will be apparent that upon rotation of gear 11 in reverse directions the member 23 will be reciprocated and due to the connection between the arms 20 and member 23, the rods 17 and 18, and the blades 14 and 15 will be oscillated. These blades have cutting edges 24 and 25 which on outward movement of the blades engage and slice the material deposited on the inner wall of the basket as indicated at 26. When substantially all of such material has been detached from the basket wall the finger 27, integral 15 with one of the arms 20, engages and closes limit switch 28 which reverses the cleaner driving motor 4 which moves the blades in a step-by-step manner towards the center of the basket. In this movement the blades scrape the dried solids 20 of the sludge on the bottom of the basket towards the center and such material drops through openings in the bottom and is carried away. The blades continue towards the center of the basket until finger 27 engages limit switch 29 which 25 reverses the motor 4 again and this cycle is repeated subject to other controls which will be explained.

Figure 4 is a general wiring diagram of the control and operating circuits of the motors and should be considered in connection with Figure 3 30 which shows additional connections in detail for control of the cleaning motor by limit switches operated thereby. In Figure 4 the line L₁, L₂ supplies current to all of the motors and other auxiliary apparatus, or certain of the auxiliary 35 devices such as the timing clocks or telecrons may be supplied from separate sources.

The main line switch 30 may be manually or electromagnetically operated and an additional line switch may be employed to be controlled by 40 a push-button or push-buttons located in convenient position at the machine.

The circuit of the low speed motor 2 may be traced (Figure 4) from L₁, switch 30, line 31, switch 13, connection 32, 32', motor 2, 32'', connection 33 to line 34, through switch 30 to L₂. The operating circuit of the cleaner motor 4, is from connection 32, on the motor side of switch 13, through 35, reversing switch 36, jogging switch 37, motor 4, lead 38, reversing switch 37 and 50 leads 39 and 33 to L₂. It will be apparent that when switch 13 is closed motor 2 will be energized and motor 4 will also be energized subject to the intermittent control by the jogging switch 37 the operation of which will be explained later.

55 The operation of the high speed motor 3 is from lead 31, reversing or plugging switch 42, lead 43, motor 3, lead 44, switch 45, lead 46, switch 42 to lead 34 to line L₂.

The valve operating motor 6 is connected in 60 parallel with motor 3 on the motor side of its controlling switch 45 so that it can be operated only during the operation of the high speed motor. The operating circuit of motor 6 is from lead 43, lead 47, motor 6, lead 48, switch 49, lead 65 50 to lead 44. Motor 6 is also provided with a reversing circuit since it must reverse in order to open and close the inlet valve to the machine. The reverse circuit for motor 6 is from 47, motor 6, lead 51, switch 52, lead 53, lead 50 to lead 44. 70 Switches 49 and 52 are interlocked so that both cannot be closed at the same time. This interlock is indicated at 54. Switch 49 is electromagnetically operated by a coil 55 which is controlled by a timing device 56 which may be an electric 75 clock or telecron. Switch 52 is electromagneti-

cally operated by a coil 57 controlled by a timing device 58 similar to 56. The timer 56 can be regulated to open the valve at a predetermined time and while the high speed motor is going up to maximum speed. The timer 58 is arranged to 5 predetermine the length of time that the valve is open which predetermines the quantity of material allowed to flow into the basket. The closing of the valve at the time set by the timer 58 will not affect the operation of the high speed 10 motor. This motor 3 is controlled through the reversing or plugging switch 42 by another timer 59 controlling coil 60.

Coil 75 controls switches 13 and 45 and is itself controlled by the governor 12 driven by the high 15 speed motor. When this motor is not running or is slowed down to a predetermined low speed the contacts controlled by governor 12 are closed, and if the line circuit is closed coil 75 will be energized to close switch 13 and open switch 45. 20 If the machine is not running, and the line circuit is closed coil 75 will be energized to open switch 45 and close switch 13. Switch 13 will then be held in closed position by holding coil 9 which is controlled by limit switch 29 (Figure 3). 25

Referring to Figure 3, the operating circuit for the cleaner motor 4 is the same as that described in Figure 4. The reversing switch 36 of this motor is controlled by two coils 61 and 62 which are controlled by the limit switches 28 and 29 which are operated by the finger 27 operated by the arm 20 which is in turn driven by the motor 4, through 10, 11, 9 and 23. Coil 61 is energized through the following circuit from connection 33, leads 63, 64, coil 61, lead 65, limit switch 28, leads 66, 67 to connection 31. The circuit for coil 62 is from connection 33, lead 63, coil 62, lead 68, limit switch 29, lead 69, lead 67 to connection 31. It will be noted that limit switch 29 has two operative positions. When 40 switch 29 is in the position shown the circuit of coil 62 is closed. When in the other operative position the holding coil 9 of switch 13 is energized. The circuit for coil 9 is from connection 33, lead 70, coil 9, lead 71, left-hand contact of 45 switch 29, lead 69, lead 67 to connection 31. Switch 29 is biased to its left-hand closed position normally.

The jogging switch 37 is operated by the jogging timer cam 19 which is driven by the jogging 50 motor 72. This motor 72 is connected in parallel with the low speed motor 2 through the following circuit, from connection 33, lead 73, motor 72, lead 74 to connection 32. It will be apparent therefore that motor 72 will be energized 55 whenever motor 2 is energized.

The circuits of coils 55, 57, 60, and 75 are not shown completed to avoid confusing the drawings with too many lines. It will be understood that these coils are connected to the line L₁, L₂ on 30 the machine side of the main switch. Likewise the usual protective devices for the motors, such as accelerating devices, overload circuit breakers, under voltage controls, and automatic setting of the timing devices, mechanical interlocks and 65 details of adjustment are omitted for the sake of clearness.

In Figure 4 the reversing or plugging switch 42 is set normally for forward running of the high speed motor. This switch is moved to its 70 reverse position by coil 60 for the purpose of plugging or decelerating by reversing its current supply. The time for energizing coil 60 and the duration of its energization is controlled by the automatic timer 59. In like manner timer 56 75

fixes the time of energization of coil 55 to start valve motor 6 in operation which may be at the time the high speed motor attains normal speed or shortly thereafter. The timer 58 determines how long the valve shall remain open and so determines the quantity of sludge to be supplied to the basket for one cycle of operation. The inlet valve 5 may be manually closed by means of hand wheel 16 in case of failure of the line current during operation of the machine.

The operation of the machine is as follows: The line switch 30 is closed manually or by push-button control on the machine, at this time the contacts controlled by governor 12 are closed so that coil 75 is energized and closed switch 13, opening switch 45, and slow speed motor 2 is set into operation. Limit switch 29 is in the position shown in Figure 3. The jogging motor 72 in parallel with motor 2 will be energized and begin rotating cam 19. If switch 37 is in closed position cleaner motor 4 will begin to rotate to move the cleaner blades 14 and 15 outwardly towards the wall of the basket. If switch 37 is not in closed position motor 72 will close it shortly after this motor becomes energized and will continue to open and close it so long as the low speed motor is energized. The cleaner blades will be given a step-by-step movement in their outward and inward travel. This is for the purpose of cutting off the accumulated material on the inner wall in layers and giving it time to pass out through openings in the bottom of the basket as the blades scrape it towards the center as they return towards that position. As soon as blade 15 moves outwardly the finger 27 releases limit switch 29 (Figure 3) and it closes the circuit of holding coil 9 of switch 13. When the cleaner blades reach their maximum outer position the finger 27 closes limit switch 28 which energizes coil 61 of reversing switch 36 which reverses motor 4 and the blades are returned to their inner or central position by a step-by-step movement scraping whatever material is in the basket towards the center where it passes out.

As the cleaner blades reach their inner position limit switch 29 will be moved to the right by finger 27 (Figure 3) to open the circuit of holding coil 9 of switch 13. During the above described operation of the slow speed and cleaner motors the high speed motor which is permanently geared to the basket will be driven by the low speed motor at such speed that governor 12 opens the circuit of coil 75. Consequently when coil 9 is deenergized by limit switch 29, switch 13 drops open and switch 45 closes. The closing of switch 10 energizes the high speed motor which begins to accelerate to the normal high speed necessary for the proper operation of the centrifugal extractor basket. Since switch 13 controls the circuits of motors 2, 12, and 4 these motors can receive no current after this switch is opened by switch 29 and these motors stop. Low speed motor 2 is not driven by high speed motor 3 due to the interposition of the free wheeling or overrunning clutch between motor 2 and the gear casing 7.

The high speed motor now accelerates until the basket has attained its normal operating speed. The timer 56 will be adjusted to energize coil 55 which operates switch 49 to start valve motor 6 to open the inlet 5 admitting sludge to the basket at a definite rate. When the valve is opened coil 55 is deenergized and the valve motor stops. The valve 5 will remain open a definite time under control of the adjustable timer 58. After a suf-

ficient quantity of sludge has passed to the machine timer 58 energizes coil 57 which through switch 52 closes a reverse circuit for motor 6 and the valve is closed and switch 52 opens leaving the valve in closed position.

At the time valve 5 is closed, or at a definite time after to give a drying period for driving all the water from the basket, the timer 59 operates to throw the reversing switch 42 which plugs motor 3 and quickly slows it down to a speed where governor 12 closes the circuit of coil 75 which opens switch 45 of the high speed motor, and timer 59 opens the circuit of coil 60 whereupon switch 42 returns to position for normal forward running of motor 3.

The closing of switch 13 energizes the slow speed motor, the cleaner motor and the jogging timer motor. The starting of the cleaner motor releases limit switch 29 which closes the holding coil 9 of switch 13 and as the slow speed motor attains normal speed governor 12 opens the circuit of coil 75 and the cycle of operation is completed and will continue automatically until stopped by the push button control or until the time circuit is opened.

From the above description it will be apparent that as the equipment is started the cleaner motor will move the cleaner blades toward the wall of the extractor basket and that the basket will be driven at slow speed. As soon as the blades reach the maximum travel position the cleaner motor will reverse and bring the blades back to the inner or center position and that the movement of the blades in both directions will be intermittent due to the operation of the jogging timer. The jogging time may be varied by varying the faces of the cam on the jogging timer. The slow speed motor operates until the cleaner blades return to their starting position and stop. The main motor will then start and accelerate to bring the extractor basket up to normal operating speed, at which time the inlet valve opens and remains open for a definite time then closes. A timer controls the length of time the main motor operates. Timers also control the time of opening and closing of the main valve and the timers are adjusted so that the valve closes before the main motor shuts down. The main motor is quickly decelerated and when it attains a definite low speed the slow speed motor starts up and takes control and the cycle of operation is automatically repeated. The free wheeling clutch between the slow speed motor and the gear drive permits the high speed motor to take up the load and lets the low speed motor stop.

It will also be apparent that when the machine is started after it has been stopped for any reason it will always start with the cleaning operation. The equipment is so arranged that if it is stopped before the end of the cycle, the individual control devices will reset and shut the equipment down, that is the sludge valve will close, the timers will reset and the motor will come to rest.

The electric control of the present invention affords the facility for varying the length of time of purging, the length of time of cleaning, the amount of inflow and the length of the post-drying period. Each one of these functions or operations may be controlled independently of the others and the control of the time and sequence of each provides means for a variable cycle of operations.

Having thus fully described my said invention,

what I claim as new and desire to secure by Letters Patent is:

- 5 1. In a centrifugal extractor for sewage sludge and other material, in combination, a centrifugal basket, a low speed electric motor for driving said basket at low speed, a high speed electric motor for driving said basket at normal extracting speed, an over-running clutch between the low speed motor and the basket, a source of current supply for said motors, and interlocked switches in the circuits of said motors and controlling their operation.
- 15 2. In a centrifugal extractor for sewage sludge and other material, in combination, a centrifugal basket, low and high speed electric motors for driving said basket, an over-running clutch between the low speed motor and the basket, a source of current supply for said motors, operating circuits connecting said source with said 20 motors, interlocked switches in said circuits, and means controlled by the speed of the high speed motor for controlling the operation of said switches.
- 25 3. In a centrifugal extractor for sewage sludge and other material, in combination, a centrifugal basket, low and high speed electric motors for driving said basket, an over-running clutch between the low speed motor and the basket, a source of current supply for said motors, 30 operating circuits connecting said source with said motors, an operating switch in the circuit of the low speed motor, an operating switch in the circuit of the high speed motor, interlocking means between said switches controlled by the speed of 35 the high speed motor for closing the low speed motor switch and opening the high speed motor switch, and means responsive to the closure of the low speed motor switch for holding said switch in closed position.
- 40 4. In a centrifugal extractor for sewage sludge and other material, in combination, a centrifugal basket, a low speed motor, an over-running clutch between said motor and said basket, a high speed motor geared to said basket, a cleaner mechanism within said basket, a cleaner motor for operating said mechanism, a source of current supply for said motors, a switch for connecting said low speed and cleaner motors to said source in parallel, a switch for connecting 45 said high speed motor to said source, and means interlocking said switches so that one is open when the other is closed.
- 55 5. In a centrifugal extractor for sewage sludge and other material, in combination, a centrifugal basket, a low speed motor, an over-running clutch between said motor and said basket, a high speed motor geared to said basket, a cleaner mechanism within said basket, a cleaner motor for operating said mechanism, a source of 60 current supply for said motors, a switch for connecting said low speed and cleaner motors to said source in parallel, a switch for connecting said high speed motor to said source, means responsive to the speed of the high speed motor for closing 65 the low speed motor switch and opening the high speed motor switch, and means responsive to the operation of the cleaner motor for holding the low speed motor switch in closed position.
- 70 6. In a control system for a centrifugal extractor, a centrifugal extractor basket, cleaner mechanism within said basket, a cleaner motor for driving said mechanism alternately in reverse directions, a reversing switch for said motor, limit switches operated by said mechanism for controlling said reversing switch, a low

speed motor for driving said basket, said motors connected in parallel, a source of current supply for said motors, and a switch controlling the circuit of both of said motors.

7. In a control system for a centrifugal extractor, a centrifugal extractor basket, a cleaner mechanism within said basket, a cleaner motor for driving said mechanism alternately in reverse directions, a reversing switch for said motor, and means controlled by said mechanism for operating said reversing switch, an intermittently operated switch in said cleaner motor circuit, a motor for driving said intermittent switch, a motor for driving said basket, a source of current for said motors and means connecting 15 said motors, to said source in parallel.

8. In a centrifugal machine for sewage sludge and other material, in combination, a centrifugal basket, an electric motor for driving said basket, an inlet valve for supplying sludge to 20 said basket, an electric motor for opening and closing said valve, a source of current supply for said motors, a switch for connecting said driving motor to said source, said valve motor connected in parallel with said driving motor on the motor 25 side of said switch, and time controlled means for controlling the valve motor.

9. In a centrifugal extractor for sewage sludge and other material, in combination, a centrifugal basket, an electric motor for driving said basket, 30 an inlet valve for supplying sludge to said basket, an electric motor for opening and closing said valve, a source of current supply for said motors, an operating switch in said driving motor circuit, said valve motor connected in parallel with said 35 driving motor on the motor side of said operating switch, a decelerating device in said driving motor circuit on the line side of said operating switch, and time controlled means for controlling the valve motor and the decelerating device. 40

10. In a centrifugal extractor for sewage sludge and other material, in combination, a centrifugal basket, low speed and high speed driving motors therefor, cleaner mechanism within the basket, a motor for driving said mechanism, an inlet valve for supplying sludge to said basket, a motor for opening and closing said valve, a source of current supply for said motors, and a switch having two operating positions in one of which it connects the cleaner and slow 50 speed motors to the source and in the other connects the high speed and valve motors to the source. 45

11. In a centrifugal extractor for sewage sludge and other material, in combination, a centrifugal basket, low speed and high speed driving motors therefor, cleaner mechanism within the basket, a motor for driving said mechanism, an inlet valve for supplying sludge to said basket, a motor for opening and closing said 60 valve, a source of current supply for said motors, means for connecting the cleaner motor and low speed motor to the source, and means responsive to an operation of the cleaner motor for disconnecting these motors and connecting the high 65 speed motor to the source.

12. In a centrifugal extractor for sewage sludge and other material, in combination, a centrifugal basket, low speed and high speed driving motors therefor, cleaner mechanism within the basket, a motor for driving said mechanism, an inlet valve for supplying sludge to said basket, a motor for opening and closing said valve, a source of current supply for said 70 motors, time controlled means for energizing the 75

valve motor to open and close the inlet valve, and time controlled means for slowing down the high speed motor.

13. In a centrifugal extractor for sewage sludge and other material, in combination, a centrifugal basket, low speed and high speed driving motors therefor, cleaner mechanism within the basket, a motor for driving said mechanism, an inlet valve for supplying sludge to said basket, a motor for opening and closing said valve, a source of current supply for said motors, means for connecting the cleaner motor and low speed motor to the source, means responsive to an operation of the cleaner motor for disconnecting these motors and connecting the high speed motor to the source, and means responsive to the speed of the high speed motor for disconnecting the high speed motor from the source and connecting the cleaner and low speed motors to the source.

14. Means for controlling the continuous cyclic operation of a centrifugal sludge extractor comprising in combination a centrifugal basket, low and high speed motors for driving said basket, cleaner mechanism within said basket, a reversible motor for operating said mechanism, means operated by said mechanism for reversing said cleaner motor, means for periodically energizing and deenergizing said cleaner motor, a jogging motor for operating said periodic means, an inlet valve for supplying sludge to said basket, a time controlled motor for opening and closing said valve, time controlled means for slowing down the high speed driving motor, means responsive to a low speed of the high speed motor to deenergize the high speed motor and energize the low speed, cleaner and jogging motors, and means responsive to an operation of the cleaner mechanism for deenergizing the low speed, cleaner and jogging motors and energizing the high speed motor.

15. In a centrifugal extractor for sewage sludge in combination, a centrifugal basket, a motor for driving said basket at low speed, cleaner mechanism within said basket, a cleaner motor for driving said mechanism, a source of current supply for said motors, and means controlled by said cleaner mechanism for reversing the cleaner motor, said means also controlling the stopping of both the low speed driving and cleaner motors.

16. In a centrifugal extractor, in combination, a centrifugal basket, a motor for driving said basket, cleaning blades located within said basket and movable back and forth from the center towards the inner wall of said basket, a cleaner motor for oscillating said blades, a reversing switch for said cleaner motor, limit switches operated by said cleaner motor in the extreme positions of said blades for operating said reversing switch, a source of current for said motors, for means connecting said motors to said source in parallel, and means controlled by one of said limit switches for controlling said means.

17. In a centrifugal extractor, in combination, a centrifugal basket, a motor for driving said basket, cleaning blades mounted within said basket to oscillate from the center towards the inner wall of said basket, a source of current supply for said motors, a switch for connecting said motors in parallel to said source, a holding coil for said switch, and means operated by said cleaner motor for deenergizing said holding coil when the cleaning blades are in their extreme center position.

18. In a centrifugal extractor, in combination,

a centrifugal basket, a motor for driving said basket, cleaning blades mounted within said basket to oscillate from the center towards the inner wall of said basket, a source of current supply for said motors, a switch for connecting said motors in parallel to said source, a holding coil for said switch, means operated by said cleaner motor for deenergizing said holding coil when the cleaning blades are in their extreme center position, and a reversing switch for the cleaner motor controlled by said means.

19. In a centrifugal extractor, in combination, a centrifugal basket, a motor for driving said basket, cleaning blades mounted for oscillatory movement in the basket, a reversible cleaner motor for oscillating said blades, a reversing switch for said cleaner motor, a periodic switch controlling said cleaner motor circuit to give a step-by-step movement of the blades in both directions, a motor for operating said periodic switch, a source of current supply for said motors, a switch for connecting said motors in parallel to said source, a holding coil for holding said connecting switch in closed position, and means operated by the cleaner motor when the blades are in extreme inner position for deenergizing said holding coil.

20. In a centrifugal extractor in combination, a centrifugal basket, low speed and high speed driving means for said basket, means for cleaning said basket, means responsive to an operation of the cleaning means for shifting the drive from the low speed to the high speed driving means, and time controlled means for shifting the drive from the high speed to the low speed driving means.

21. In a centrifugal extractor, in combination, a centrifugal basket, a motor for driving said basket, cleaning blades mounted for outward and inward movement in the basket, a reversible cleaner motor for oscillating said blades, and means including a periodic switch for periodically operating the said cleaner motor to give the cleaning blades a step by step outward movement.

22. In a centrifugal extractor, in combination, a centrifugal basket having a bottom discharge opening, a motor for driving said basket, cleaning blades mounted for outward and inward movement in the basket and having portions traversing the bottom of the basket, a reversible cleaner motor for oscillating said blades, and means including a periodic switch for periodically operating the said cleaner motor to give the cleaning blades a step by step inward movement to deflect the material on inward movement of the cleaner blades to said discharge opening.

23. In a centrifugal extractor, in combination, a centrifugal basket, a motor for driving said basket, cleaning blades mounted for outward and inward movement in the basket, a reversible cleaner motor for oscillating said blades, and means including a periodic switch for periodically operating the said cleaner motor to give the cleaning blades a step by step outward and inward movement.

24. In a control system for a centrifugal extractor, a basket, cleaner mechanism for said basket, an electric motor for driving said mechanism alternately in reverse directions, a reversing switch for said motor, and means controlled by said mechanism for operating said reversing switch, an electric motor for driving said basket, and means for connecting said motors in parallel to a source of current supply.

25. In a centrifugal extractor for sludge or oth-

- per material comprising in combination, a centrifugal basket, an electric motor for driving, said basket, means for feeding sludge to said basket, an electric motor for operating said feeding means, a source of current supply for said motors, an operating switch in said driving motor circuit, said feed motor circuit connected to said driving motor circuit on the motor side of said switch, a decelerating device in said driving motor circuit on the line side of said switch, and time controlled means for controlling said feed motor and said decelerating device.

26. In a centrifugal extractor for sludge and other materials, in combination, a centrifugal basket, low speed and high speed driving motors therefor, cleaner mechanism for said basket, a motor for driving said mechanism, means for feeding sludge to said basket, a motor for operating said feeding means, a source of current supply for said motors, and switch means for connecting said low speed and cleaner motors to said source under certain conditions, and said high speed and feeding motors to said source under other conditions.

27. In a centrifugal extractor for sewage sludge and other material, in combination, a centrifugal basket, low and high speed electric motors for driving said basket, a source of current supply for said motors, operating circuits connecting said source with said motors, interlocked switches in said circuits and means controlled by the speed of the high speed motor for controlling the operation of said switches.

28. In a centrifugal extractor for sewage sludge and other material, in combination, a centrifugal basket, a low speed motor, a high speed motor for driving said basket, cleaner mechanism within said basket, a cleaner motor for operating said mechanism, a source of current supply for said motors, a switch for connecting said low speed and cleaner motors to said source in parallel, a switch for connecting said high speed motor to said source, and means interlocking said switches so that one is open when the other is closed.

29. In a centrifugal extractor for sewage sludge and other material, in combination, a centrifugal basket, a low speed motor, a high speed motor for driving said basket, cleaner mechanism within said basket, a cleaner motor for operating said mechanism, a source of current supply for said motors, a switch for connecting said low speed and cleaner motors to said source in parallel, a switch for connecting said high speed motor to said source and means interlocking said switches so that one is open when the other is closed, and control means for said switches insuring that on starting the low speed and cleaner motor switch will close before the high speed motor switch is closed.

30. In centrifugal separating equipment, a basket, driving means for rotating the basket, feeding means introducing material to be treated, cleaning means for removing compacted solids from the wall of the basket, and a control system for controlling the actuation of the driving, feeding and cleaning means in cyclic operation including mechanism actuating said three means to provide operation of the driving means and feeding means, and simultaneous operation of the

driving means and cleaning means, and mechanism cooperatively associated with the control means for said driving mechanism and the control means for said cleaning means for insuring initial actuation of the cleaning means upon initial operation of the equipment even when the operation has previously been stopped at a different point in the cycle of operation.

31. In centrifugal separating equipment, a rotary centrifugal basket, spaced vertical rods extending into the basket, horizontally swinging scrapers carried by the rods and operating within the basket, lever arms connected with the rods, a slideable member operatively connected with the lever arms, a motor means operatively connecting the motor and said slideable member and actuated by said motor for sliding the slideable member for simultaneously swinging the scrapers, and means for periodically interrupting swinging movements of the scrapers to produce step-by-step movements of the scrapers during their swinging movements.

32. In centrifugal separating equipment, a rotary centrifugal basket, scrapers mounted in the basket for outward and inward movement therein, a motor having operative connection with the scrapers for actuating the scrapers, and means for periodically interrupting the outward and inward movements of the scrapers to give the scrapers step-by-step outward and inward movements.

33. In centrifugal separating equipment, a rotary centrifugal basket, scrapers mounted in the basket for outward and inward movements within the basket, a motor operatively connected with the scrapers for actuating the same to give to them said outward and inward movements, and means for periodically interrupting the movements of the scrapers during their outward movement to give them a step-by-step outward movement.

34. In centrifugal separating equipment, a rotary centrifugal basket, scrapers mounted in the basket for outward and inward movement within the basket, a motor operatively connected to the scrapers for actuating the same and means for periodically interrupting the inward movement of the scrapers to give the scrapers a step-by-step inward movement.

35. In centrifugal separating equipment, a rotary centrifugal basket, a scraper mounted in the basket for outward and inward movement within the basket, a motor operatively connected with the scraper for moving the same, and means for periodically interrupting movement of the scraper to give it step-by-step movements.

36. In a centrifugal separating equipment, a rotary centrifugal basket, high speed driving means for the basket including an overrunning clutch having cooperating driving and driven parts, the latter of which is permanently geared to and rotative with the basket, scrapers mounted for outward and inward movement in the basket, and means operatively connected to the scrapers for imparting a step-by-step movement to the scrapers while the basket is being rotated by the high speed driving means.

JOSEPH S. PECKER.

CERTIFICATE OF CORRECTION.

Patent No. 2,080,874.

May 18, 1937.

JOSEPH S. PECKER.

It is hereby certified that error appears in the printed specification of the above numbered patent requiring correction as follows: Page 3, first column, line 56, for "10" read 45; and page 5, first column, line 60-61, for "for means" read means for; and that the said Letters Patent should be read with these corrections therein that the same may conform to the record of the case in the Patent Office.

Signed and sealed this 29th day of June, A. D. 1937.

Henry Van Arsdale

(Seal)

Acting Commissioner of Patents.
